corporation of Ohio

Application May 5, 1939, Serial No. 84,812

To all whom it may concern:

Be it known that I, John H. Sutter, a citizen
of the United States, residing at New York city,
in the county of Kings and State of New York,
have invented a new, original, and ornamental
Design for a Hollow Glass Building Block, of
which the following is a specification, reference
being had to the accompanying drawing, forming
a part thereof.

In the drawing:

Fig. 1 is a perspective view of a hollow glass
building block showing my new design embodied
therein.

Fig. 2 is a fragmentary sectional view taken
along the line 2—2 of Fig. 1 showing the con-
tour of the inner surface. The opposite face of
the block is of the same design as the one il-
lustrated.

The ornamental design for a hollow glass
building block, substantially as shown and de-
scribed.
